HYDRAULIC SYSTEM CONTROL MEANS

Emert J. Lattner, Cedar Rapids, Iowa

Application May 4, 1936, Serial No. 77,780

2 Claims. (Cl. 103—42)

This invention relates to oil burners and has particular relation to means for removing air from the fuel supply, pumping, and control means of such burners.

In setting up oil burners it is necessary to remove air from the fuel supply means, from the pumping means, and from the various conduits employed for supplying fuel to the nozzle, as it is otherwise difficult, if not impossible, for 10 the pump to pull the oil into the system. This is particularly true when the supply tank is located below the level of the oil burner. However, I have discovered that if the return or re-circulation line is vented to atmosphere to 15 permit the pump to drive air out of the system and replace the air with liquid fuel, the air may be removed from the system and the vent then closed to permit pumping the fuel to the nozzle. At the same time the return line beyond the 20 vent must be closed to prevent loss of vacuum during venting and opened when exhaustion of the trapped air has been completed. These operations must be accomplished simultaneously and practically instantaneously.

It is, therefore, a general object of my invention to provide means for starting the flow of fuel oil to the nozzles of oil burners and to avoid the difficulties, some of which are enumerated above.

It is another general object of my invention to provide, in an oil burner fuel supply system, readily operable vent means to facilitate driving air from the system.

It is another object of my invention to provide, in an oil burner fuel supply system, means for venting the system to the atmosphere and at the same time closing off the return line and in another position of the control means to close the vent to atmosphere and open the return line.

It is still another object of my invention to provide venting means of the above character which may be incorporated in the conventional strainer, pump, and control valve structure used with oil burners.

Other and further features and objects of the invention will be more apparent to those skilled in the art upon a consideration of the accompanying drawing and following specifications, wherein is disclosed a single exemplary embodiment of the invention, with the understanding, however, that such changes may be made therein as fall within the scope of the appended claims, without departing from the spirit of the invention.

In said drawing:

Figure 1 is a side elevational view of an oil burner as it appears installed and of the fuel supply tank and the control means for controlling the flow of fuel to the nozzle of the oil burner.

Figure 2 is a diagrammatic illustration showing the flow of oil from the supply tank to the nozzle of a burner, together with a view in section of one embodiment of my invention, and

Figure 3 is a view in section of a venting device 10 constructed according to one embodiment of my invention as it appears incorporated in the conventional combination strainer, pump and control valve means of an oil burner.

Referring now to the drawing, and more particularly to Figures 1 and 2 thereof, there is illustrated at 10 generally a fuel supply tank having a filling pipe 11 and vent pipe 12 in accordance with the usual construction.

A fuel supply line 13 is provided and the flow 20 of fuel into this line is controlled by the shut-off valve 14 at the supply tank 10. In operation the fuel passes from the tank 10 through the valve 14 and supply line 13 and into the strainer 16 through the shut-off valve 15. The fuel then 25 passes from the strainer 16 to the pump 17 and into the control valve 18. The control valve 18, as here shown, is a two part valve in which the upper part 18a houses a valve mechanism which permits fuel to flow through the nozzle (not 30 shown) when fuel pressure of the order of forty pounds is reached. The size of the opening in the nozzle varies in accordance with the heating capacity of the burner, but the quantity of flow of oil from the nozzle is always considerably less 35 than the quantity of flow from the pump 17. The lower part 18b of the valve 18 houses another valve mechanism which becomes operative under pressures of the order of one hundred pounds to permit oil to be returned or by-passed 40 through a return line 19 to the strainer 16. However, there is a small opening 20 through this valve at all times to permit a limited flow of fuel through the return line 19 even when the valve 18b is closed. The flow of fuel in the sys- 45 tem of Figure 1 at the burner is diagrammatically illustrated in Figure 2 but with the addition of a venting device 21 constructed according to one embodiment of my invention, this venting device being located in the return line 19. 50

Referring now to Figure 2, oil from the supply tank passes through the line 13 into the pump 17 and from the pump to one side of the valves 18a and 18b corresponding to the upper and lower portion of the valve 18 of Figure 1. The pump 55

17, for instance, may be so designed as to pump twenty-two gallons of fuel per hour. The nozzle at 22, for instance, may be set to pass only two gallons of fuel per hour. The valve 18a, furthermore, may be set at a pressure of forty pounds and the valve 18b at one hundred pounds. It is obvious that if the pump 17 is started up with fuel in the system, the valve 18a will be opened first and fuel will flow at the rate of two gallons per hour from the nozzle 22. Since the pump 17 delivers twenty-two gallons of fuel per hour, pressure within the line 23 leading to the valves 18a and 18b will soon exceed one hundred pounds and the excess oil will return to the line 19 and back into the strainer 16. A small portion of the fuel from the pump will be by-passed through the opening 20 of valve 18b at all times while the pump is pumping fuel.

Now if air is trapped in the system illustrated in Figure 2, as it is when the system is first started or is started after a period of idleness, the pump 17 probably will not draw the fuel into the system. The air within the system is merely driven by the pump through the opening 20 and return line 19 and back to the intake of the pump to be re-circulated over and over in the same manner. By reason of the greater compressibility of the trapped air as compared to fuel it will pass through the small by-pass 20 before its pressure is raised sufficiently to raise the valve 18a from its seat to permit the trapped air to be driven through the nozzle.

If, however, the line 19 is vented to atmosphere and closed beyond the vent, the air will be pumped out of this system through this vent and oil will begin to flow out through the vent. If the return line 19 is then opened back to the line 13 and the vent closed, this flow of oil will continue and the oil will be pumped out of the nozzle 22 and excess oil flow back through the line 19 and into the supply line 13 to permit normal operation of the burner.

Preferred embodiments of my invention are illustrated in Figures 2 and 3. In Figure 2 the venting device 21 is comprised of a cylinder 24 having a cylindrical chamber 26 therein. Fuel from the line 19 passes into the chamber 26 through an intake port 27 and may either pass out through the return line port 28 or out through a drain or vent port 29 in accordance with the position of the double faced valve 31. In the normal position of the valve 31 the spring 32 lifts the lower valve face off of the seat 34 to thus open the return line port 28, the upper face 36 of the valve being held against the seat 37 by the pressure of the spring 32 to close the vent port 29.

In order to vent air from the system and from the return line 19 the button 39 is depressed to thus open the vent port 29 and close the return line port 28. Air within the return line 19 is thus driven out into the atmosphere. When oil begins to flow out of the vent port 29 the valve button 39 is released and the vent port 29 is thus closed and return line port 28 opened to permit oil to be returned to the strainer 16.

Devices constructed according to my invention may be incorporated in combined strainer, pump and valve structures such as shown in Figure 3. The structure here shown is comprised of a strainer 41, a gear pump, the teeth of which are indicated at 42, and a control valve structure indicated generally at 43. The pump is driven by means of the shaft 44 from an electric motor (not shown) or other power source. While the struc-

ture shown in Figure 3 is a combination of several units, its operation generally is similar to the structure disclosed in Figures 1 and 2. Fuel enters into the strainer 41 through the port 46 and passes through the strainer and up into the main body of the structure through the channel 47 as indicated by the arrows. From the channel 47 the fuel passes into the spaces between the teeth of the gear pump and is discharged through the channel 48 into the chamber 49 beneath the valve piston 51. A small by-pass 50 permits a limited flow of fuel into the chamber 57 and channel 58 through the port 60 and chamber 68 and back into the channel 47 leading to the pump. As the pressure beneath the piston 51 builds up, the valve disc 55 of piston 51 is lifted from its seat and the fuel then flows through the channel 53 and through the nozzle of the burner.

In a given structure, for instance, the nozzle may only discharge on the order of two gallons of fuel per hour and the pump may pump as much as twenty-two gallons per hour, therefore the piston is raised still further until the port 54 is uncovered. Fuel then passes from the chamber 49 through the port 54, around the wall of the cylinder, and out through the port 56 and into the chamber 57. Fuel then flows through the channel 58 to the cylindrical chamber 59 of a valve structure which is substantially the same as that shown in Figure 2.

If the double faced valve 61 is in the down position, as here shown, entrapped air may pass out through the discharge opening 62 and be discharged through the channel 63 in the valve button 64. Inasmuch as the valve face 61 closes the channel 66, the entrapped air cannot be returned to the channel 47. When fuel begins to flow from the channel or port 63 pressure on the button 64 is released, and the upper face of the double valve 61 closes the channels 62 and 63 by being seated by reason of the action of the spring 67 on the valve stem button 64, and thus opening the entrance to the conduit 66. Fuel oil then passes through the channel 66 into the chamber 68 and back into the channel 47 where it may be re-circulated.

It is apparent that the vent valve structure selectively either closes the by-pass or return channel and opens a vent to the atmosphere or closes the vent to the atmosphere and opens the by-pass channel. The device shown in Figure 3 operates in substantially the same manner as the device shown in Figures 1 and 2 and air is permitted to pass out of the system by depressing the venting valve until oil begins to flow from the valve. When oil begins to flow the venting valve is released and the oil will at once circulate through the system.

Although I have described a specific embodiment of my invention, it is apparent that modifications thereof may be made by those skilled in the art. Such modifications may be made without departing from the spirit and scope of my invention as set forth in the appended claims.

I claim as my invention:

1. In an oil burner including a fuel supply line, a pump, a return line from the discharge side of the pump to the intake side, a pressure valve for regulating the flow of fuel through the return line, the pressure valve having an air vent port leading from the discharge side of the pump to the return line, and a two seated vent valve in the return line adapted when in position on one seat to close off the portion of the return line between the intake side of the pump and the valve and to

vent to atmosphere the remaining portion of the return line between the valve and the discharge side of the pump, and when in position on the other seat to close off the vent to atmosphere and to open the return line.

2. In an oil burner including a fuel supply line, a pump, a return line from the discharge side of the pump to the intake side, a pressure valve for regulating the flow of fluid through the return line, the pressure valve having an air vent port from the high pressure side of the valve to the return line, a valve means for selectively venting the return line to atmosphere and closing the vent to atmosphere and opening the return line comprising a cylindrical member in the return

line having an opening therethrough communicating with the atmosphere, a valve having the stem thereof extending within the opening of the cylindrical member, the valve being adapted to seat on the cylindrical member to close the aforesaid opening therethrough and the valve also being adapted to seat in the return line to close off the return line between the seat and the intake side of the pump, a spring on the valve stem for keeping the valve normally seated on the aforementioned cylindrical member, and a push button on the valve stem adapted to be manually depressed to seat the valve in the return line for venting the return line to atmosphere.

EMERT J. LATTNER. 15
